OF NEW YORK, N. Y., A CORPORATION OF NEW YORK

CLOSURE

Application filed December 7, 1928. Serial No. 324,443.

This invention relates to closures for containers, such as metallic barrels.

One of the objects of the invention is to provide an improved closure, in which the component elements are so designed as to enable them to be economically and otherwise satisfactorily made by stamping operations, and to provide a closure which is strong, durable and reliable in use.

10 The invention, of which several forms are herein shown and described, will be understood from the following description taken in connection with the accompanying drawings, in which, Figure 1 is a bottom view of one form of cap; Figure 2 is a sectional view taken on line 2—2 of Figure 1; Figure 3 is a bottom view of a closure similar to that of Figure 1, but having a cover or top member of a slightly different contour; Figure 4 is a bottom view of a larger type of closure, having another modified form of cover or top member; Figure 5 is a sectional view of a closure similar to those shown in Figures 1—4, but having the re-enforcing flange turned upwardly; Figure 6 is a bottom view 20 of a closure, having a cover or top member of the form shown in Figure 1 interlocked with the gasket supporting flange of a screw threaded cup-shaped member; Figure 7 is a sectional view taken on line 7—7 of Figure 6; Figure 8 is a bottom view of a closure, having a cover or top member of the form shown in Figure 3 interlocked with the gasket supporting flange of a screw threaded cup-shaped member which is slightly different to that shown in Figure 6; and, Figure 9 is a bottom view of a closure, having a top member of the form shown in Figure 4 interlocked with the gasket supporting flange of a screw 30 threaded cup-shaped member of a slightly different form to those shown in Figures 6 to 8 inclusive.

Although certain forms of the invention are herein shown in connection with small 45 closures and other forms of the invention are shown in connection with larger closures, it will be understood that the sizes of the embodiments of the invention may be varied as desired without departing from the spirit of 50 the invention, as for example, the closures

shown in Figures 1 to 3 inclusive and in Figures 5 to 8 inclusive may be made of a size corresponding to that of the closures shown in Figures 4 and 9, and that the forms of the invention shown in these latter Figures may be made in the size of the forms of the invention shown in Figures 1 to 3 and 5 to 8.

Each of the closures herein shown comprises a cover or top member of a non-circular wrench-receiving contour which includes 65 a plurality of wrench-receiving ears or lugs, the cover member being provided with a re-enforcing flange which may be turned downwardly or upwardly as desired at the outer margins of the ears and along the outer margin of the cover member intermediate such ears, there being associated with the cover or top member a screw threaded cup shaped member which is adapted to be screwed down into a suitable screw threaded sput of a container wall.

According to this invention, the form of the cover or top member may vary, and likewise the form of its associated screw threaded cup shaped member may also vary, as illustrated in the accompanying drawings.

Referring to Figures 1 and 2, the cover or top member 15 is shown as having a non-circular wrench-receiving contour and including a plurality of outwardly projecting ears 16, between which the peripheral margin of the cover member is curved, such curved portions lying on a circle struck from the center of the top member. In order to strengthen the cover or top member 15 including the outwardly projecting ears 16, such cover is provided with a continuous re-enforcing flange 17, which is formed at the outer edge of the top member intermediate the ears 16 thereof and about the outer margin of such ears. This re-enforcing flange 17, materially re-enforces the top member 15 against buckling or other distortions in screwing the closure down into sealing engagement on a container, and particularly 95 re-enforces the ears 16 against bending stresses or other forces, as when a wrench is applied to the closure intermediate such ears for screwing the closure down into sealing position or as when a hammer is employed 100

to impart a releasing impact to the ears for loosening the closure from its sealing position to enable it to be readily removed from a container. Attached to the top member 15, 5 is an externally screw-threaded cup-shaped member 18, having a bottom wall which fits into a depression 19 formed centrally in the top member. This depression is of such size, with reference to the outside diameter of the 10 cup-shaped member 18, as to snugly receive the bottom of the cup-shaped member and facilitate centering of the cup-shaped member with respect to the top member during 15 assembling. This cup-shaped member 18 is attached to the cover member 15 by electrically 20 welding its bottom thereto at a suitable number of points 20, herein shown as three. If more than one weld is employed, the bottom of the cup shaped member is struck up 25 at a number of points, corresponding to the number of welds desired, prior to welding, so as to provide a plurality of projections which serve to concentrate the welding current at the points of connection, as will be 30 readily understood, such projections being herein omitted from the drawings inasmuch as they disappear or flatten out due to their heated condition at the instant of welding.

Referring to Figure 3, the construction is 35 the same as that of Figures 1 and 2 except the outer margin of the top member 15' intermediate the outwardly projecting ears 16' are bent down along straight rather than curved lines, thus forming straight sides 23, 40 intermediate the ears 16', which sides are adapted for the reception of a wrench to be used in screwing the closure into and out of sealing position. The re-enforcing flange 17' in this form of the invention, as in the form 45 of closure shown in Figures 1 and 2, serves to strengthen the top member 15' and the ears 16' which form a part of that member. The screw threaded cup-shaped member 18' is located within a central depression 19' formed in the top member 15', as described in connection with the form of invention shown in 50 Figures 1 and 2, and may be connected to the top member by welding its bottom thereto at a single point shown at 24 or at a plurality of points as shown at 20 in Figures 1 and 2.

Referring to Figure 4, the construction is the same as that of Figure 3 except that the top member 15'' is larger and is formed with a greater number of straight sides 23'', herein 55 shown as six in number, and with a greater number of ears 16'', herein also shown as six in number. In this form of the invention, the screw threaded member 18'' is identical with the screw threaded members 18 60 and 18' except as to size, and may be attached by welding its bottom to the top member 15'' within the central depression 19'' at a plurality of points 20' as described in connection with the form of invention shown in 65 Figures 1 and 2.

Referring to Figure 5, the top member 15a may have the contour shown in Figures 1, 3 or 4, and differs from any one of such forms only in that its re-enforcing flange 17a is turned upwardly instead of downwardly. It 70 will be understood that the cup-shaped member 18a, is positioned within in a central depression 19a formed in the top member 15a, and is there welded to such top member at a plurality of points as described in connection with Figures 1 and 2, or at a single point 75 as described in connection with the form of invention shown in Figure 3.

In the closure shown in Figures 6 and 7, the top member 15b is preferably formed with 80 a square central wrench-receiving opening 26 about which preferably depends a relatively narrow skirt 27, which serves to reinforce the top member 15b in the vicinity of its opening against torsional strains when a 85 wrench of suitable design is introduced into the opening 26 and employed to screw the closure into and out of sealing position. The top member 15b is provided with a re-enforcing flange 17b which serves to strengthen 90 the top member including its wrench receiving ears 16b, as above described. In the present form of the invention, a screw threaded cup-shaped member 29 is employed, 95 which is provided at its open end with an outwardly projecting gasket supporting flange 30 which is secured to the cover member 15b by welding at spaced points as shown at 31. This gasket supporting flange 30 is 100 preferably provided on its periphery with a plurality of projections 32 which project into the spaces afforded between portions of the re-enforcing flange 17b at opposite sides of the ears 16b and there established an interlocking engagement between the flange 30 105 of the cup-shaped member 29 and its associated top member 15b, the projections 32 being relatively short so as to extend only a short distance into the ears 16b. This interlocking engagement between the gasket supporting flange 30 and the re-enforcing flange 17b facilitates centering of the top member 15b and the cup-shaped member 29 preparatory to welding the gasket supporting flange 110 to such top member; and, after such welding, the gasket supporting flange 30 serves to reinforce the flange 17b against bending or distortion, when it is subjected to forces incident to the use of a wrench or other tool 115 in screwing the closure into or removing it from a sput or fitting.

In the closure shown in Figure 8, a top member 15c is employed which is identical with the top member 15b above described 120 except as to contour, and in this respect it resembles the top member 15' shown in Figure 3. The top member 15c is provided with a re-enforcing flange 17c, having a plurality of straight side portions 23'', 125 130

herein shown as four in number, and with a corresponding number of ears 16c. The screw threaded cup shaped member 29', is identical with the cup shaped member 29 shown in Figures 6 and 7, except that the peripheral contour of its gasket supporting flange 30' conforms to the inner walls of the straight side portions 23'' of the re-enforcing flange 17c and thereby establishes an interlocking and reinforcing engagement of the cup shaped member 29' with the top member 15c, which members are permanently connected together by welding at a plurality of points, as shown at 31'. As in Figures 6 and 7, the central wrench receiving opening 26' of the top member 15c leads into the cup shaped member 29' and is adapted for the reception of a suitable wrench to be used in screwing the closure into and out of sealing position, it being understood that the wrench receiving opening 26' may be re-enforced by a depending skirt 27' corresponding to the re-enforcing skirt 27 shown in Figure 7.

In the closure shown in Figure 9, a top member 15d is employed which has the outer contour of the top member 15'' of Figure 4 and is formed with a central wrench receiving opening 26'' which as in Figures 6 to 8 is re-enforced by a depending re-enforcing skirt 27''. The screw threaded cup shaped member 29'' in the present instance also resembles the screw threaded cup shaped member 29 shown in Figure 7, except that its gasket supporting flange 30'' is so shaped as to present a plurality of straight edges which conform to and engage the inner walls of the straight side portions 23''' of the re-enforcing-flange 17d which serves to re-enforce the top member 15d including its ears 16d. By reason of the engagement of the gasket supporting flange 30'' with the straight sided portions 23''' of the re-enforcing flange 17d, an interlocking and reinforcing connection is established between the cup shaped member 29'' and its associated top member 15d which is welded to the gasket supporting flange at a plurality of points as shown at 31''.

In each form of the invention herein shown, a suitable gasket 35 (Figures 1, 2, 5, 6 and 7) may be employed. This gasket will be backed up, in the forms of the invention shown in Figures 1 to 5 inclusive, by the respective top members 15, 15', 15'' and 15a; and in the forms of the invention shown in Figures 6 to 9 inclusive, this gasket 35 will be backed up by the respective gasket supporting flanges 30, 30' and 30'', the gasket being in all instances forced into intimate engagement with a suitable gasket seat on the container spout (not shown), whereby an adequate seal may be provided for the container with which the closures are employed.

In order that a suitable sealing wire may

be employed in connection with the several forms of closures, the ears thereof are provided with perforations 40 through which the sealing wires, not shown, may be threaded, such wires being also suitably attached or anchored to the container walls according to usual practice.

What is claimed is:

1. A closure comprising a sheet metal cover member having a non-circular peripheral wrench receiving contour and including a plurality of ears projecting therefrom, said cover plate being provided with a continuous re-enforcing flange at the outer margins of said ears and along its outer margin intermediate said ears, and an externally screw threaded member welded to said cover member and spaced at all points on its threaded periphery a substantial distance from said flange whereby a gasket seat is provided between the threaded periphery of said screw threaded member and the re-enforcing flange of said cover member.

2. A closure comprising a sheet metal cover member having a non-circular wrench receiving contour and including a plurality of ears projecting therefrom, said cover plate being provided with a re-enforcing flange at the outer margins of said ears and along its outer margin intermediate said ears, and a screw threaded member welded to said cover member, said screw threaded member having portions thereof cooperating with said re-enforcing flange whereby said cover member and screw threaded member have interlocking and re-enforcing engagement with one another.

3. A closure comprising a sheet metal cover member having a non-circular wrench receiving contour and including a plurality of wrench receiving ears projecting therefrom, said cover plate being provided with a re-enforcing flange at the outer margins of said ears and along its outer margin intermediate said ears, and a screw threaded member welded to said cover member, said screw threaded member having an outwardly projecting non-circular gasket supporting flange having portions cooperating with said re-enforcing flange whereby said cover member and said screw threaded member have interlocking and re-enforcing engagement with one another.

4. A closure comprising a sheet metal cover member having a non-circular wrench receiving contour and including a plurality of ears projecting therefrom, said cover plate being provided with a re-enforcing flange at its outer margin, and a screw-threaded member welded to said cover member, said screw-threaded member having a portion thereof cooperating with said re-enforcing flange whereby said cover member and said screw-threaded member have interlocking and re-enforcing engagement with one another.

5. A closure comprising a sheet metal cover member having a non-circular wrench receiving contour and including a plurality of wrench receiving ears projecting therefrom, said cover plate being provided with a re-enforcing flange at its outer margin, and a screw-threaded member welded to said cover member, said screw-threaded member having an outwardly projecting non-circular gasket supporting flange cooperating with said re-enforcing flange whereby said cover member and said screw-threaded member have interlocking and re-enforcing engagement with one another.
